UNITED STATES PATENT OFFICE.

WILLIAM BAUMGARTNER, OF MENDOCINO CITY, CALIFORNIA.

SIGNAL-SOUNDER.

1,113,400.

Specification of Letters Patent. Patented Oct. 13, 1914.

Application filed April 6, 1914. Serial No. 829,781.

To all whom it may concern:

Be it known that I, WILLIAM BAUMGARTNER, a citizen of the United States, residing at Mendocino City, in the county of Mendocino and State of California, have invented 5 certain new and useful Improvements in Signal-Sounders, of which the following is a specification.

My invention relates to that class of signal-sounders in which reeds are vibrated by 10 a fluid current under pressure.

My invention is applicable to any use requiring the sounding of a signal, the volume of sound being controlled by the size of the 15 device and its tone or pitch being in accordance with the reeds used. The pressure current may be steam, or air, or any gaseous fluid and the source of pressure may be varied according to circumstances and the 20 use to which the device is put. For the sake of illustration and description, I will disclose the device in the shape of a horn, such as may be used for automobiles, though it is to be understood that it may assume various 25 shapes and sizes and it may be provided with various sound-amplifiers.

The object of my invention is to provide a simple signal-sounder, adapted for wide 30 limits of volume and pitch, and to this end my invention consists in the novel signal-sounding device which I shall now fully describe by reference to the accompanying drawings, in which—

Figure 1 is a longitudinal section of my 35 device, the sound-amplifier being in elevation. Fig. 2 is a perspective view of the pair of opposing spaced reeds. Fig. 3 is a cross section on the line $x-x$ of Fig. 1. Fig. 4 is a cross section on the line $y-y$ of 40 Fig. 1.

1 is a union indicating a connection for the device to any suitable source of fluid-pressure.

2 is a pipe-section forming the housing for 45 the reeds. This housing is fitted at its rear end to the union 1, and said rear end carries a cross bar 3. In the forward end of the housing is fitted or provided a barrier or block 4 with a slot 5. To the forward end 50 of the housing 2 is fitted a sound-carrying pipe 6, the rear end of which is enlarged to form a chamber 7 which, from its function, may be termed a reverberating chamber.

55 To the forward end of the pipe 6 is fitted the sound-amplifier or trumpet 8. The

reeds are 9. These, in their best form, are metallic. There is a pair of these reeds which may be formed of a single piece bent double or two separate pieces. The reeds 60 lie opposite and spaced from one another. At their rear ends they are fitted into the cross bar 3 of the reed-housing 2. They thence pass forwardly in said housing, wholly free thereof and of each other, and 65 freely through the slot 5 in the forward block 4 and their extremities are best caused to diverge or separate as shown at 10, said extremities lying within and being enveloped by the reverberating chamber 7 of the 70 pipe 6.

In operation, the fluid pressure admitted to the rear end of the reed-housing 2 and passing out through the contracted slot 5 of the block 4 will cause the reeds to vibrate, 75 and their free extremities acting very much like the lips of a human operator will, in conjunction with the reverberating chamber, produce a characteristic sound very serviceable as a signal.

I claim:

1. In a signal-sounder, the combination of a pipe for receiving a pressure fluid-current; a pair of opposing, spaced reeds within said pipe, said reeds being fixed at one end and 85 thence extending in the same direction as the flow of the fluid current; and a slotted barrier in the pipe, through the slot in which the free extremities of the reeds pass and beyond which they project.

2. In a signal-sounder, the combination of a pipe for receiving a pressure fluid-current; a pair of opposing, spaced reeds within said pipe, said reeds being fixed at one end and 95 thence extending in the same direction as the flow of the fluid current; and a slotted barrier in the pipe, through the slot in which the free extremities of the reeds pass and beyond which they project, said pipe having an enlarged chamber enveloping the free extremities of the reeds.

3. In a signal-sounder, the combination of a pipe for receiving a pressure fluid-current; a pair of opposing, spaced reeds within said pipe, said reeds being fixed at one end and 105 thence extending in the same direction as the flow of the fluid current; and a slotted barrier in the pipe, through the slot in which the free extremities of the reeds pass and beyond which they project, said pipe having 110 an enlarged chamber enveloping the free extremities of the reeds, and said reed extremi-

ties within said chamber being divergent one from the other.

4. In a signal-sounder, the combination of a pair of opposing, spaced reeds; a housing for said reeds having a support at its rear end in which the rear ends of the reeds are fixed, and a slotted block at its forward end through the slot in which the forward ends of the reeds pass and beyond which they project; a sound carrying pipe secured to the forward end of the reed-housing and enveloping the projecting ends of the reeds beyond the slotted block; and a connection with a source of fluid-pressure at the rear end of the reed housing.

5. In a signal-sounder, the combination of a pair of opposing, spaced reeds; a housing for said reeds having a support at its rear end in which the rear ends of the reeds are fixed, and a slotted block at its forward end through the slot in which the forward ends of the reeds pass and beyond which they project; a sound carrying pipe secured to the forward end of the reed-housing and formed with an enlarged chamber enveloping the projecting ends of the reeds beyond the slotted block; and a connection with a source of fluid-pressure at the rear end of the reed housing.

20 6. In a signal-sounder, the combination of a pair of opposing, spaced reeds having their forward ends divergent one from the other; a housing for said reeds having a support at

its rear end in which the rear ends of the reeds are fixed, and a slotted block at its forward end through the slot in which the reeds pass and beyond which their forward divergent ends project; a sound-carrying pipe secured to the forward end of the reed-housing and enveloping the projecting divergent ends of the reeds beyond the slotted block; and a connection with a source of fluid-pressure at the rear end of the reed housing.

35 7. In a signal-sounder, the combination of a pair of opposing, spaced reeds having their forward ends divergent one from the other; a housing for said reeds having a support at its rear end in which the rear ends of the reeds are fixed, and a slotted block at its forward end through the slot in which the reeds pass and beyond which their forward divergent ends project; a sound-carrying pipe secured to the forward end of the reed-housing and formed with an enlarged chamber enveloping the projecting divergent ends of the reeds beyond the slotted block; and a connection with a source of fluid-pressure at the 40 45 50 55 rear end of the reed housing.

8. In testimony whereof I have signed my name to this specification in the presence of two subscribing witnesses.

WILLIAM BAUMGARTNER.
